UNITED STATES PATENT OFFICE

110,094

DESIGN FOR A DRESS

Jacob J. Kushner, New York, N. Y.

Application April 23, 1938, Serial No. 76,709

Term of patent 3½ years

To all whom it may concern:

Be it known that I, Jacob J. Kushner, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the specific appliquéd on the lower waist portion of the specific dress shown.

I claim:

The ornamental design for a dress, substantially as shown and described.

JACOB J. KUSHNER.
